UNITED STATES PATENT OFFICE.

AUGUSTIN GAGNÉ, OF CENTRAL FALLS, RHODE ISLAND, ASSIGNOR, BY MESNE ASSIGNMENTS, TO HEMPHILL COMPANY, OF PAWTUCKET, RHODE ISLAND, A CORPORATION OF MASSACHUSETTS.

STOP-MOTION AND ALARM MECHANISM FOR KNITTING-MACHINES.

1,375,217.

Specification of Letters Patent. Patented Apr. 19, 1921.

Application filed September 13, 1917. Serial No. 191,098.

To all whom it may concern:

Be it known that I, AUGUSTIN GAGNÉ, a subject of Great Britain, residing at Central Falls, in the county of Providence, State of Rhode Island, have invented a certain new and useful Improvement in Stop-Motion and Alarm Mechanisms for Knitting-Machines, of which the following is a specification, reference being had therein to the accompanying drawings.

The features of the invention are applicable in connection with circular knitting machines. The invention includes devices of novel character for detecting a fault, more especially needles which have lost their heels or butts through breakage, in which latter instance such devices are operative to detect a needle which occupies an unretracted position at a point in the circuit of the needle-carrier at which it should occupy a retracted position. One of the said features consists in means for withdrawing the detector from its working position, as for instance prior to reciprocating knitting, so as in such instance to take it out of the path of needles which are given raised or projected positions in order to render them inoperative to knit, and are caused to remain therein during the reciprocating knitting, as in knitting the heel and toe of a stocking. The invention includes, also, improved tripping, unshipping, and shipper devices for knitting machines, especially adapted for employment in combination with automatic stop-motion devices, including yarn stop-motions.

Figure 1 of the drawings shows in side elevation, with small portions of certain parts broken away, a circular knitting machine having embodiments of the features of the invention applied thereto. The said machine is of the well-known Banner type which is disclosed as to its main features in Letters Patent of the United States No. 933,443, granted under date of September 7, 1909, to J. D. Hemphill.

Fig. 2 is a partial rear elevation of the said machine with the said embodiments of the features of the invention applied thereto, with the machine standing at rest.

Fig. 3 is a detail sectional view of the shipper and certain parts in connection therewith, in the same positions as those occupied by them in Fig. 2.

Figs. 4 and 5 are detail views of the de- 55 tent-lever constituting an element of the stop-motion mechanism.

Fig. 6 is a plan view of the needle-cylinder of the said machine and certain parts adjacent thereto, including elements of the 60 stop-motion devices, with the needle-detector in normal working relations with the needle-circle.

Fig. 7 is a view on the same order as Fig. 6, but showing the needle-detector as having 65 been engaged and moved by a needle which has not been retracted, and the associated stop-motion parts in the resulting positions.

Fig. 8 is a view on the same general order as Figs. 6 and 7, showing the needle-detector 70 retracted by the action of the automatic means provided to effect such relation, as for reciprocating knitting.

The machine that is partly shown in the drawings by way of illustrating a practical 75 application of the features of the invention is an automatic stocking machine of a make that is extensively in use at this time. The general construction, mode of operation, etc., of the said machine are not material 80 so far as the invention is concerned.

The drawings show the usual rotating needle-cylinder N of the Banner type of machine, the circular series of needles n² carried thereby, a sinker-bed n⁶, a sinker-cam- 85 plate G, a latch-ring C, and yarn-guides d'. Also a main-shaft s with loose or idle-pulley p², slow-speed-pulley p', and quick-speed-pulley p, all mounted thereon, a driving-band p³, a shipper p⁵ carrying the fork p⁵¹ 90 embracing one run of the driving-band p³, a pattern-barrel-shaft s', and a shipper-controlling pattern-cam-wheel p⁶ mounted on said pattern-barrel-shaft s'. Shipper p⁵ is shown mounted as usual upon a fixed rod 95 p⁵² projecting from machine-frame a, and adapted to slide along the said rod to enable it to occupy successive positions corresponding with the respective band-pulleys. At v' is a latch which, by entering a notch in a bar p⁵ attached to shipper p⁵ and projecting inward therefrom, locks the shipper in the position shown in Figs. 2 and 3, namely, with the driving-band upon the loose or idle pulley p² and the machine stopped.

As heretofore, during the operation of the machine the position of the shipper p⁵ is controlled, to determine which band-pulley the

- driving-band p^3 shall work upon at a given time, by means of the pattern-cam-wheel p^6 and its various outstanding flange-segments. As heretofore, also, the shipper is acted upon by a spring, herein the spring 1, which acts with a tendency to move the shipper inward toward the machine-frame, so that when the latch v' is disengaged from the bar p^x in connection with the shipper the said spring 5 will thus move the shipper, and thereby transfer the driving-band p^3 from the loose or idle pulley to one of the other pulleys. In beginning a stocking the transfer of the driving-band is to the quick-speed-pulley p .
- 10 During the working of the machine the spring keeps the downward projection of the shipper pressed against the portions of the pattern-cam-wheel which successively are presented thereto by the intermittent rotation of said wheel, so that the position of the shipper at successive stages of the knitting is determined by the narrow flange-segments of the pattern-cam-wheel, and by the gaps or low places between segments. The spring 15 is specially combined and related, as a feature of the invention, as explained later herein. p^{61} is the flange projection upon the said pattern-cam-wheel which acts to move the shipper p^5 into position to place the driving-band upon the loose or idle-pulley p^2 for the purpose of bringing the machine to rest at the proper stage in a series of operations.
- 20 Referring now to the devices for detecting a fault at or in connection with the needles, I have shown devices for detecting a needle which occupies an unretracted position at a point in the circuit of the needle-cylinder at which it should occupy a retracted position:
- 25 When the heel or butt of a needle, or portion furnished with such heel or butt, breaks off so that the usual cam-devices cannot act upon such needle to move it endwise, the needle consequently will remain in whatever position was last given to it. For the detection of a needle which remains unretracted instead of being properly retracted, at a particular point in the circuit of the needle-cylinder, a detector 2, shown in Figs. 1 and 2, but also shown to best advantage in Figs. 30 6, 7, and 8, is provided. This detector is mounted adjacent the needle-cylinder in a manner enabling it when in its working position to project, as in Fig. 6, inwardly above the top rim of the needle-cylinder and the 35 circle of needles, at a point where the needles normally should be in retracted relations with respect to the needle-cylinder in being carried around by the rotation of the latter. The said detector is shown in the drawings 40 immediately over the drawing-down point in the machine. See Fig. 1, in which a portion of standard K has been broken away to expose the needles and detector to view. It is located in such relation to the drawing-down cam and at such a height with reference to the tops of the needles that the needles which possess butts or heels and are drawn down properly before arriving at the detector will clear the latter by passing onward entirely below it. The said height, 45 however, is such that in case a needle occupying a projected position in advance of the drawing-down point should have lost its heel or butt, so that the needle is not properly retracted by the drawing-down cam at the drawing-down point, the upper end of the unretracted needle will be carried against the detector 2 by the rotary movement of the needle-cylinder. As such movement of the cylinder continues the unretracted needle thus engaged with the detector will push the detector around with it.
- 50 To permit the detector to be pushed ahead by the needle which has engaged the same, the detector is secured to a carrier 3 which is mounted in a manner giving it capacity for unison-movement with the needle-cylinder. The required movability of the detector and detector-carrier under the action of the said needle is provided for in the case 55 of the illustrated embodiment by pivoting the carrier at 3' to a support 4, so as to adapt it to swing in a horizontal plane. The projected needle by pushing against the detector 2 operates to turn the detector and carrier around the vertical pivot 3', as into the 60 position shown in Fig. 7. The turning movement thus communicated to the detector and its carrier is utilized to bring about stopping of the machine.
- 65 The specific character of the devices through which stopping is brought about under control of the needle-detector 2 may vary more or less in practice, in some cases. The drawings show illustrative devices for 70 the purpose, including spring-actuated devices adapted to actuate the shipper p^5 to transfer the driving-band p^3 from either the quick-speed-pulley p or the slow-speed-pulley p' (whichever it happens to be upon) 75 to the loose or idle-pulley p^2 , detent-means serving to hold said spring-actuated devices in an inoperative state in readiness to act, and means through which the detector-device disengages the detent when moved by 80 a needle which has engaged therewith, so as by such release to permit the said spring-actuated devices to bring about movement of the shipper to transfer the driving-band to the loose or idle pulley p^2 .
- 85 The said spring-actuated devices comprise a rockshaft 6 which is mounted in bearings at 7, 7, in connection with the adjacent side-portion of the machine-frame a , an arm 5 fixed to the front end of the said rockshaft, a pin 18 carried by the said arm, and a contracting spiral spring 16 extending from arm 5 to a fixed arm 17 carried by the outer end of shipper-support p^{52} . The 90 said spring acts with a tendency to rock the 95
- 100 105 110 115 120 125 130

arm and rockshaft outwardly so as to cause the pin 18 to engage with the shipper and move the latter outward to place the band-pulley p^3 upon the loose or idle driving-band p^2 . Normally, however, the rockshaft 6 is kept locked from turning through the action of the detent-means mentioned above, with the arm 5 and pin 18 in a position close to the adjacent side of the machine, as in Figs. 2 and 3. This position of the arm and pin leaves the shipper free to occupy a position holding the driving-band upon quick-speed-pulley p , or one holding the band upon slow-speed-pulley p' . Upon the disengagement of the detent-means the spring 16 acts to rock the arm and rockshaft outward so that through the engagement of the pin 18 with the shipper the latter is moved outward and the driving-band thereby is transferred to the loose or idle pulley p^2 .

The detent-means comprises, in the illustrative form thereof shown in the drawings, an arm 8, Fig. 1, that is fixed upon the rockshaft, and a detent-lever 9 having its lower end constructed to engage with the top of the arm 8 in manner indicated in Fig. 1, so as by such engagement to prevent the rockshaft 6 from turning under the action of spring 16. The detent-lever 9 is disposed in an upright position, and pivoted at 10 in connection with a suitable support 11. A spring 12, Fig. 1, in connection with the detent-lever holds its lower end in engagement with the arm 8, and keeps a projection 9^a of the detent-lever pressed against one side of the arm 8, such projection serving to prevent the end of the detent-lever from being swung too far forward, past the arm 8, by the action of the spring 12, in entering into engagement with the arm. The unlocking of the rockshaft to free it to the action of the spring 16, so that it may be rocked by the agency of the latter, is effected by swinging the detent-lever around its pivot 10 so as to disengage the detent-lever from arm 8 by a rearward movement.

Referring now to the means through which the detector-device disengages the detent when moved by a needle which has engaged therewith.

In the illustrated embodiment thereof the carrier 3 of the detector 2 is combined operatively with the detent-lever 9 by means of a link 13, an upright lever 14, and a horizontal tripping-lever 15. The link 13 connects carrier 3 with the upright-lever 14. The lower arm of lever 14 extends into proximity to the inner arm of the horizontal tripping-lever 15. The outer arm of the tripping-lever 15 extends alongside the top end of the detent-lever 9. When the detector and its carrier are swung around the pivot 3' in consequence of the engagement of an unretracted needle with the detector, the link 13 transmits movement to the upright

lever 14 by which the latter is swung around its pivot 14^a, and the said lever through engagement with the inner arm of the horizontal tripping-lever 15 causes the latter to swing around its pivot 15^a. Through the engagement of the outer arm of the tripping-lever with the upper arm of the detent-lever 9, the latter is swung around its pivot 10 so as to disengage its lower end from the arm 8 of the rockshaft 6, thereby unlocking the said rockshaft.

From what already has been stated it will be clear that upon the disengagement of detent-lever 9 from arm 8 the rockshaft is rocked outwardly through the action of the contracting spiral spring 16, and as the arm 5 is swung outwardly the pin 18 carried thereby engages with the shipper 5 and acts to move the shipper outward along support p^{52} , thereby transferring the driving-band p^3 from whichever pulley, p or p^2 , it has been working upon over to the loose or idle pulley p^2 , and thus bringing about the stopping of the machine.

For the purpose of keeping the lower end of the detent-lever 9 rearward of the arm 8 after the latter has been swung outward by the rocking of the rockshaft 6, in order that by reason of the said lower end being thus kept rearward the said end shall be prevented from being drawn forward past the arm 8 by the action of the operating spring 12, the said lower end of the detent-lever carries a lateral projection 19, which is so arranged that when the detent-lever is swung around its pivot 10 to carry its lower end rearward out of engagement with the arm 8 of the rockshaft 6, and the said rockshaft is turned by the action of spring 16, such turning carries the arm 8 upward in front of the lateral projection 19. Arm 8 then by engagement with the front face of the lateral projection 19 keeps the engaging portion of the detent-lever at the rear of the arm 8. When the operator, by taking hold of the crank-handle 20 upon the rockshaft 6, rocks the said rockshaft reversely so as to swing arm 5 and its pin 18, as well as arm 8, inwardly, the tension of the spring 12 will operate to draw the engaging end of the detent-lever 9 forward over the top of the arm 8 and into locking engagement therewith as soon as the said arm 8 has been depressed sufficiently to permit such action to take place.

In practice, knitting machines having the features of the present invention applied thereto will be equipped with devices of approved character for detecting breakage or failure of a yarn or yarns on the way from the source of supply to the needles, or the occurrence of knots, or an excess of tension in a yarn. Fig. 1 shows a rod 21 extending downward from the usual position of these additional devices over the head of the ma-

chine, which rod is arranged in any approved manner heretofore usual or preferred for vertical movement downward on the occurrence of one of the contingencies for which provision is made in the case of the overhead devices. Said figure shows also a bell-crank 22 arranged to be operated by downward movement of the rod 21, this bell-crank being connected by a link 23 with the 10 horizontal tripping-lever 15, so that downward movement of the rod 21 will operate the tripping-lever 15 to disengage the detent-lever 9 to provide for an unshipping action substantially such as has been explained, to bring about stopping of the machine.

Referring now to the means for withdrawing the detector 2 from its normal working position, prior to the performance of reciprocating knitting:

The support 4 for the detector-carrier 3 has capacity for movement for the purposes of such withdrawal. In the illustrative embodiment of the invention, the said support 25 4 is an arm, which is pivoted at 4^a, in Figs. 6, 7, and 8, and is connected by means of a link 24 to one arm of a bell-crank 25 at the side of the machine the other arm of which, as shown best in Figs. 1 and 2, is connected 30 by a downwardly extending link 26 to one arm of a lever 27. A contracting spiral spring 28, Fig. 1, in connection with this lever operates through the connections which have been described to hold the support 35 4 normally in the working position shown in Figs. 6 and 7. A pattern-cam 29 upon the pattern-barrel-shaft s' actuates the lever 27 to move the support 4 from its working position in Figs. 6 and 7 to its withdrawn position shown in Fig. 8, so as thereby to move the detector 2 from its working 40 position above the circle of needles into a retracted position entirely clear of the said circle of needles. As an acting portion of 45 cam 29 releases the lever 27 the spring 28 restores the support 4 and needle-detector to working position. In the present case, the cam 29 is formed and related properly to cause the withdrawal of the needle-detector 50 2 for and during reciprocating knitting in knitting a heel, and also for and during reciprocating work in knitting a toe, and to permit the detector to occupy the desired working relations with respect to the needles 55 during circular or round-and-round knitting.

Preferably an audible alarm is provided in order to attract the operator's attention when the stop-motion devices act. Such an alarm is illustrated in Figs. 1 and 2. Fig. 1 shows a bell 30 (which is omitted from Fig. 2 in order to avoid concealing parts which it is desired to show in such view) which is conveniently mounted upon an edge of the bed-plate a². A clapper-lever 31 is mounted 60 65 upon the upper arm of the detent-lever 9 by

means of a pivot-screw 32. This clapper-lever is furnished with a pin 33 projecting laterally in proximity to the upper run of the driving-band p³, and of a length sufficient to extend across the width of the band-pulleys p, p', p², for coöperation with one or more striker-blocks 34 attached to the exterior surface of the driving-band. The extent of turning movement of the clapper-lever 31 relative to the detent-lever is limited by means of a stop-pin z upon the upper arm of the detent-lever, with which stop-pin the tail of the clapper-lever engages. So long as the detent-lever is in position for engagement with the arm 8 of the rockshaft 80 6, the pin 33 is held clear of the path of the striker-block or striker-blocks 34 of the driving-band. When, however, the detent-lever is swung around its pivot 10 so as to disengage its lower end from the arm 8, and is temporarily locked in its new position through the engagement of arm 8 with the laterally-projecting piece 19, the pin 33 is brought and held closer to the surface of the upper run of the driving-band and is struck 90 by the striker-block 34, or each thereof in succession in case more than one such striker-block is provided, and as a result of the pin being struck by a striker-block, the clapper-lever is thrown toward the bell so 95 as to cause it to strike the latter and make a sound.

A special feature in connection with the spring 1 by means of which the shipper p⁵, when unlatched by the disengagement of the latch v', is moved inward to place the driving-band upon one or the other of the pulleys p' and p, as the case may be, is the fact that such spring is connected at its inner end to the arm 5 of the rockshaft 8. By reason of this connection with the arm 5, instead of to a fixed point in connection with the machine-frame, the spring 16 is relieved of the work of overcoming the tension of the spring 1 is operating to move the shipper outward by rocking the arm 5 and rockshaft 6 outwardly after the unlocking of the rockshaft by the disengagement of the detent-lever 9 from the arm 8. The spring 16, therefore, does not need to be as strong as it would have to be if the spring 1 extended from the shipper to a fixed point on the machine-frame. Assuming that while the machine stood at rest the shipper was locked in this outermost position by means of the latch v', the operation of rocking the rockshaft 6 by hand reversely, to move the arm 5 inward and reengage the arm 8 with the detent-lever 9, will have the effect of stretching both springs 1 and 16, thereby placing 110 115 120 125 130 spring 1 in a proper state of tension to draw the shipper inward as soon as the latch v' is disengaged from the shipper, in addition to placing the spring 16 in proper tension to rock the arm 5 outward to effect unshipping

upon the subsequent unlocking of the rock-shaft 6.

What is claimed as the invention is:—

1. Stop-motion and alarm devices for knitting machines comprising a shipper, a spring-actuated rockshaft for actuating said shipper to unship the driving-power, a detent for holding said rockshaft restrained in readiness to act in moving said shipper, a detector adapted to be actuated by a needle which remains unretracted and through which the detent is actuated to release the rockshaft, and an alarm-device having a striker-device connected with said detent and called into action by such actuation of the detent.
2. Stop-motion and alarm devices for knitting machines comprising a shipper, a spring-actuated actuator for the said shipper to cause it to effect unshipping, a detent for said actuator, detector-means through which the detent is operated to release the actuator, a moving piece adapted to act as a cam, and an audible-alarm-device having a striker which is moved into the path of said cam by the detent when the latter is operated.
3. Stop-motion and alarm devices for knitting machines comprising a shipper, a spring-actuated actuator for the said shipper to cause it to effect unshipping, a detent for said actuator, a detector adapted to be actuated by a needle which remains unretracted and through which the detent is operated to release the actuator, a moving piece adapted to act as a cam, and an audible-alarm-device having a striker which is moved into the path of said cam by the detent when the latter is operated.
4. In a knitting machine, the combination with a group of band-pulleys, a shipper, and a pattern-cam-wheel controlling the position of the said shipper, of a spring-actuated actuator for the said shipper by which the latter is operated to unship the driving-power, detent-means by which said actuator is controlled, and a spring connecting said shipper to said actuator, operating to hold the shipper against the pattern-cam-wheel.
5. In a knitting machine, in combination, a group of band-pulleys, a shipper, a pattern-cam-wheel controlling the position of the shipper and driving-band relative to the band-pulleys, a spring-actuated rockshaft for actuating said shipper to ship the driving-band upon the loose or idle pulley, detent-means for restraining said rockshaft, and a spring connecting said shipper to said rockshaft, operating to hold the shipper against the pattern-cam-wheel.
6. In a knitting machine, in combination,

a group of band-pulleys, a shipper, a pattern-cam-wheel controlling the position of the shipper relative to said band-pulleys, a spring-actuated rocker for actuating said shipper to ship the driving-band upon the loose or idle pulley, detent-means for restraining said rocker, a latch for holding the shipper in position adjacent the loose or idle pulley, and a spring connecting the shipper to the rocker adapted to draw the shipper toward the pattern-cam-wheel when said latch is disengaged.

7. A circular knitting machine comprising a fault-detector having a detecting position adjacent the needle-circle, a normally stationary support for said detector relative to which the latter is moved on detection of a fault, and means for automatically operating said support, to withdraw said fault-detector from proximity to the needles when reciprocation of the cylinder is to take place.

8. A circular knitting machine having a rotating needle-cylinder, stop motion devices including a normally stationary detector-support, a detector movably combined therewith and projecting across the needle-circle at a point where the needles normally occupy a retracted position, arranged to be cleared by the retracted needles and to be engaged and operated to call the stopping of the machine by a needle which occupies an unretracted position by reason of loss of its heel or butt, and means for automatically operating said detector-support and thereby withdrawing said detector clear of the needles when reciprocation of the needle-cylinder is to take place.

9. A circular knitting machine having stop-motion devices including a normally stationary detector-support, a detector movably combined therewith which projects across the needle-circle at a point where the needles normally occupy a retracted position, arranged to be cleared by the retracted needles and to be engaged and operated to call the stopping of the machine by a needle which occupies an unretracted position by reason of loss of its heel or butt, and a pattern-cam operatively connected with said detector-support and by which the latter is operated and the detector withdrawn clear of the needles when reciprocating work is to be performed.

In testimony whereof I affix my signature in presence of two witnesses.

AUGUSTIN GAGNÉ.
